UNITED STATES PATENT OFFICE.

WILLIAM ALLEN, OF OVERBROOK, KANSAS.

FUNNEL.

Application filed June 19, 1924. Serial No. 720,929.

To all whom it may concern:

Be it known that I, WILLIAM ALLEN, a citizen of the United States, residing at Overbrook, in the county of Osage and State of Kansas, have invented certain new and useful Improvements in Funnels, of which the following is a specification, reference being had to the accompanying drawings.

10 This invention relates to funnels, more particularly of a kind useful in filling barrels or drums of larger size such as ordinarily employed in transporting heavy oils or other liquids. Barrels or drums of this type are usually constructed of metal, being as a result heavy and unwieldy, and therefore difficult to handle, and moreover, on account of having their bung or filling holes in the ends or heads, cannot, with aid of 15 ordinary funnels, be readily filled when lying horizontal in which position they are generally arranged for convenience in storing and shipping.

The purpose of my invention is to enable 20 filling of horizontally lying barrels or drums, and to provide a very simple and efficient means to this end capable of easy application to the barrels or drums, and of engaging them for support in such a 25 manner as to be self sustaining against dislodgment during filling.

The advantages accruing to my invention 30 will become readily apparent from the detailed description hereinafter of a typical embodiment thereof, the appended claims serving to define those features which I believe to be new and novel, and therefore patentable.

With reference to the drawings, Fig. I is 35 a perspective view showing the manner in which my improved funnel is used in filling a barrel or drum.

Fig. II is a fragmentary sectional view 40 showing how the funnel is held in position on the barrel or drum; and,

Fig. III is a detail cross section taken as indicated by the arrows III-III in Fig. II.

In these illustrations, the main or body 45 portion of the funnel indicated at 1, is represented as being horizontally disposed, and constructed of sheet metal fashioned to rectangular configuration with a rolled head 2 about the upper edge for better security and rigidity of the structure against rough or careless handling. Attached in

spaced parallel relation along the bottom of the body portion 1 of the funnel as by soldering or welding, are a pair of longitudinally-extending runners or skids 3, 3 also preferably formed of sheet metal bent to channel cross section, and adapted to rest upon the up-side of a horizontally-lying barrel or drum B as shown in Fig. I with the body portion bridging the rotundity of 55 the side after the manner of Fig. III. By this provision, the funnel may be used in filling barrels or drums of all sizes irrespective of differences of curvature or irregularities in them, and with assurance of 60 firm support thereon.

The bottom of the main or body portion 1 of the funnel is appropriately sloped to insure complete drainage of the contents through an outlet opening 4, at one end. 65 Leading rearwardly from this opening 4, beneath, and in spaced relation to the bottom of the body portion 1, is a spout 5 that is somewhat curved or pitched at a declination toward its discharge end as shown to 70 best advantage in Fig. II. The drain spout 5 may be rigidly joined with fluid tightness to the main or body portion 1 of the funnel in any convenient way, for example by providing the same with an integral flange 6 capable of being soldered, 75 welded or riveted to a circumferential margin about the outlet opening 4.

In use, the end of the drain spout 5 is introduced into the filling aperture or bung hole H in the head of the barrel or drum B, and the body portion 1 at the same time slid along the up-side of said barrel or drum until movement is intercepted by wedging 80 engagement of the top surface of the sloping 85 spout with the contiguous region of the edge of the bung hole H. Thus, by virtue of the declination of the spout 5, and through cooperation of the skids 3, the funnel is 90 clampingly held to, and stabilized on the barrel against the possibility of being 95 displaced during filling.

From the foregoing it will be seen that 100 with the aid of my improved funnel, the filling of barrels or drums is greatly expedited, without necessitating their being turned end up but leaving them in a horizontal position thereby allowing them to be rolled out of the way as they are successively filled.

Having thus described my invention, I 110 claim:

1. A funnel comprising a horizontally-disposed body portion, and a spout leading rearwardly beneath, and in spaced relation to the body portion so as to enable its insertion into the bung hole into the end of a horizontally lying barrel, and the body portion to be supported upon the up-side of the barrel.

2. A funnel comprising a horizontally-disposed body portion; and a spout leading rearwardly at a declination beneath, and in spaced relation to the body portion so as to enable its insertion into the bung hole in the end of a horizontally lying barrel, and by virtue of its inclination to clampingly hold the funnel with the body portion resting upon the up-side of the barrel.

3. A funnel comprising a horizontally-disposed body portion with spaced skids extending longitudinally along its bottom; and a spout leading rearwardly beneath, and in spaced relation to the body portion so as

to enable its insertion into the bung hole of a horizontally-lying barrel, and the body portion to be supported with its skids resting 25 upon the up-side of the barrel.

4. A funnel comprising a horizontally-disposed body portion with spaced skids extending longitudinally along its bottom; and a spout leading rearwardly at a declination beneath, and in spaced relation to the body portion so as to enable its insertion into the bung hole of a horizontally-lying barrel, and by virtue of its inclination to cooperate with the skids of the body portion 30 in clampingly holding the funnel against displacement on the up-side of the barrel.

In testimony whereof, I have hereunto signed my name at Overbrook, Kansas, this 11th day of June, 1924.

WILLIAM ALLEN.
